UNITED STATES PATENT OFFICE.

JOHN A. MINGER, OF BERN, KANSAS.

WASHING-MACHINE.

1,301,292.

Specification of Letters Patent. Patented Apr. 22, 1919.

Application filed June 1, 1918. Serial No. 237,804.

To all whom it may concern:

Be it known that I, JOHN A. MINGER, a citizen of the United States, residing at Bern, in the county of Nemaha and State of 5 Kansas, have invented certain new and useful Improvements in Washing-Machines, of which the following is a specification.

This invention relates to improvements in washing machines, and has for one of its 10 objects to combine in one machine the advantages of a suction and rubbing action on the garments within a receptacle.

Another object of the invention is to provide a device of this character of improved 15 construction and increased efficiency wherein the requisite movements of the combined suction and rubbing element is accomplished by actuating an operating lever externally of the receptacle or tub for the garment.

20 Another object of the invention is to provide a device of this character wherein the parts are readily assembled and which may be separated for renewal or repairs of impaired portions without discarding the remaining portions.

With these and other objects in view, the invention consists in certain novel features of construction, as hereinafter shown and described and then specifically pointed out 30 in the claims; and in the drawings illustrative of the preferred embodiment of the invention—

Figure 1 is a vertical sectional elevation, Fig. 2 is a plan view,

35 Fig. 3 is a bottom plan view of the combined suction and rubbing portion of the device,

Fig. 4 is a side elevation illustrating the arrangement of the operating lever mechanism,

40 Fig. 5 is a detached perspective view of the oscillating arm.

The improved device may be arranged in connection with any desired form of tub or 45 receptacle for the garments, but for the purpose of illustration an ordinary round or circular tub is shown and indicated as a whole at 10. The receptacle is suitably mounted upon supporting legs indicated at 50 11 and provided with a detachable closure 12 hingedly united to the body of the tub at one side, as shown.

Disposed upon the top 12 centrally thereof 55 is a supporting bracket including a bearing 13 to support the upper end of a standard or shaft 14. The standard 14 extends into

the interior of the body 10 and is then directed at an angle to the vertical axis of the portion 14 of the standard as shown at 16.

Mounted for rotation upon the portion 16 60 of the standard is a combined rubbing and suction producing device comprising a shell portion 17 open at the lower side. Mounted upon the closed side of the shell 17 is a tubular socket device 18 having a laterally 65 directed flange 19 bearing upon the outer face of the shell. The socket device 18 extends through the shell and in advance of its lower open face, the obliquely directed portion 16 of the standard extending 70 through the socket and held against withdrawal by a transverse pin 20 inserted through it adjacent the end of the socket. Fitting over the protruding terminals of the socket and of the standard is a rubbing 75 block 21 having a lateral flange 22 at its inner end corresponding substantially to the flange 19 of the socket. The flanges 19—22 are coupled by a plurality of tie rods 23 so that the shell is firmly coupled to the socket. 80 The pin 20, by engaging against the end of the socket, prevents withdrawal of the standard from the socket.

Disposed within the shell 17 are a plurality of radially extending partitions 24 forming a plurality of independent compartments within the shell as illustrated in Fig. 3. At their inner ends the partitions 24 bear against the outer face of the socket 18 and conform in outline to the inner face of 90 the shell 17. At their outer ends the partitions depend below the line of the shell and are formed with recesses 25 in their lower edges whereby rubbers 26 are produced. The partitions are secured in place by screws 95 or like devices 27 passing through the side of the shell into the ends of the partitions, and the lower edges of the partitions, at their inner ends, bearing upon the flanges 22. By this arrangement the shell 17, the socket 18 100 with its flange 19, the rubbing block 21 with its flange 22, and the partitions 24 are firmly united and held in position by the coaction of the bolts 23 and screws 27. When the portion 14 of the standard is rotated the 105 shell and the parts associated therewith will be swung around the vertical axis of the standard in an inclined position and caused to roll over the clothes in the tub, rotating about its own axis in the direction opposite 110 to the direction of rotation of the standard, thus bringing the compartments formed by

the partitions 24 consecutively into their lowest point.

Formed through the upper end of the shell 17 between the partitions 24 are openings 28. In the illustration shown in Fig. 3 six of the radial partitions 24 are shown, thus producing six compartments within the dolly and each compartment is provided with an opening 28. Attached to the outer 10 face of the shell and extending over each alternate opening 28 is a cage 29 in which a valve 30 is disposed and operates to close the upper side of the opening. Attached to the inner face of the shell and extending over 15 each of the remaining alternate openings 28 is a similar cage 31, and disposed within each of the cages 31 is a similar valve 32 operating to bear over the inner side of the adjacent opening 28. Thus one-half of the 20 compartments are provided with outwardly opening valves and the remaining half of the compartments provided with inwardly opening valves.

The compartments operate as air cups, 25 and as the shell is rotated the compartments or cups move downwardly against the garments and into the water at one side and rise above the water and away from the garments at the other side. In those chambers 30 or compartments which have the valves on the inner side of the shell, as the compartment moves downwardly against the clothes the valve will be closed and compression produced in the compartment while as the 35 compartment rises from the water the valve will open and a suction will be created through the compartment. In the alternate compartments, which have the valves on the outside, suction occurs as the compartments 40 move downwardly and compression occurs as the compartment moves upwardly. The result of this operation of the valves is to set up a very thorough circulation of the water through the compartments and the 45 clothes and cause the clothes to be sucked into the alternate compartments whereby they will be drawn across the rubbers and agitated throughout their mass, the dirt being rapidly removed.

50 Connected to the portion 14 of the standard externally of the top 12 of the receptacle is a gear pinion 33, and surrounding the pinion and connected to the bearing 13 is a cage-like structure 34. Connected to the 55 body 10 of the receptacle at one side and near the upper and lower portions are bracket devices 35 through which a vertical shaft 36 is mounted for rotation.

Attached to the free edge of the closure 60 12 is a bracket 54 having a bearing sleeve 55 at its outer end, the center of the bearing sleeve being in alignment with the shaft 36 and receiving the upper end of the latter. Disposed above the bearing sleeve 55 is

an arm 37 having a depending hub 56 rotatably engaging in the bearing sleeve 55. The shaft 36 is provided with a transverse pin 57 extending through the shaft and engaging in transverse recesses or seats 58 in the hub 56. By this arrangement the arm 70 37 is rotatably mounted upon the sleeve 55 of the bracket 54 and moves with the closure 12 when the latter is disposed in open position, and is automatically coupled to the shaft 36 when the closure 12 is in its 75 downward position as shown in Fig. 1. The shaft 36 remains in position supported by the bearings 35, and the arm 37 is moved away from the shaft with the closure 12 when the latter is disposed in open 80 position. Pivoted at one end to the arm 37 is an operating bar 38 having a rack 39 engaging the pinion 33 at one side. Pivoted to the arm 37 at the opposite end is a bar 40 having a rack 41 engaging the 85 pinion 33 at the opposite side. The bars 38-40 operate one above the other, and the pinion 33 is of sufficient length to permit the bars to thus operate thereon without interference. The cage 34 is preferably provided with vertically directed guide portions 42-43 having guideways to respectively receive the bars 38-40. The bars 38-40 are preferably provided respectively with vertical guide ribs 44-45 which engage through seats in the guideways 42-43. 90 By this means the bars are maintained in proper position relative to the pinion, and operate without cramping. The seats in the members 42-43 are formed with curved 95 contiguous faces as indicated by dotted lines in Fig. 2, so that the swinging movement of the bars when the arm 37 is actuated will not cause the bars to cramp in the seats. At its lower end the shaft 36 is provided 100 with an operating arm 47 with which an operating rod 48 is connected. Pivoted at 49 to a bracket 50 attached to the body 10 is an operating lever 51 terminating in a handle 52 at one end and pivoted at 53 to 105 the opposite end of the rod 48. By this arrangement it will be obvious that when the lever 51 is vibrated upon its pivot 49, the rod 48 will correspondingly oscillate the arm 47 and the shaft 36 and thus produce alternate rotary motion to the shaft member 14, and alternately rotate the shell 17 and its attachments.

110 The parts are so proportioned that each vibration of the lever 51 will cause the shell 120 17 to alternately complete a full revolution at each movement.

115 The improved apparatus is effectual in operation, can be inexpensively manufactured and produces a rapid alternating suction and compression action upon the clothes. The water is thus drawn through the garments by the suction at one side of

the shell and produces a rubbing and "pounding" action at the opposite side of the shell.

Having thus described the invention, what 5 is claimed as new is:

1. A washing machine comprising a shaft mounted for rotation and having a portion extending obliquely to the longitudinal axis thereof, a shell mounted for rotation on the 10 obliquely directed portion of the shaft and divided by radial partitions into a plurality of downwardly opening air chambers whereby the chambers are consecutively compressed against the garments and elevated 15 therefrom, an inwardly opening valve connected to each alternate air chamber, and an outwardly opening valve connected to each of the remaining alternate air chambers.
  - 20 2. A washing machine comprising a shaft mounted for rotation and having a portion extending obliquely to the longitudinal axis thereof, a tubular support rotative on the obliquely directed portion of the shaft and including a lateral flange, a shell engaging 25 said flange, a rubbing block bearing over the inner end of the shaft, a plurality of
- partition members radially disposed within the shell and bearing at their inner ends against the tubular member whereby a plurality of air chambers are formed, an inwardly opening valve connected to each alternate air chamber and an outwardly opening valve connected to each of the remaining alternate air chambers, and 30 35 clamping devices connecting the flange of the tubular member to the rubbing block.
3. A washing machine comprising a shaft mounted for rotation and having a portion extending obliquely to the longitudinal axis thereof, a shell mounted for rotation on the obliquely directed portion of the shaft and divided by radial partitions into a plurality of downwardly opening air chambers whereby the chambers are consecutively compressed against the garments and elevated therefrom, an inwardly opening valve connected to each alternate air chamber, an outwardly opening valve connected to each of the remaining alternate 40 45 air chambers, and means for oscillating said shaft.

In testimony whereof I affix my signature:
JOHN A. MINGER. [L.s.]
